COMB FOR TREATING THE SCALP

Willy Jaberg, Zurich, Switzerland

Application October 7, 1953, Serial No. 384,563

Claims priority, application Switzerland October 8, 1952

3 Claims. (Cl. 132—115)

The treatment of the scalp with liquids or ointments is rendered difficult owing to the fact that the liquid or ointment cannot be brought on to the scalp through the hair but is wholly or for the larger part intercepted or absorbed by the hair. This drawback has a disadvantageous effect especially in home treatment, in the case of which no other expedient is available, and, apart from insufficient treatment of the scalp, it causes a disproportionately large consumption of liquids or ointments with which the scalp is to be treated. This drawback is obviated by the present invention.

The subject matter of the present invention is a comb for treating the scalp, the teeth of which are provided with bores which pass through them longitudinally and in each of which there is provided a valve which is kept closed by spring action and the valve cone of which is provided with a pin for opening the valve, which pin projects from the tip of the tooth and passes through the bore with clearance, a container for the substance intended for the treatment of the scalp being arranged on the back part of the comb.

Since, on using this comb, the liquid or ointment intended for the treatment of the scalp issues at the tips of the teeth, which slide on the scalp, the liquid or ointment is applied to the scalp directly.

An example of embodiment of the subject matter of the invention is represented by the accompanying drawings, of which

Fig. 1 is a longitudinal medial section through a comb for treating the scalp, and shows a device which may optionally be used for applying pressure to material within the comb;

Fig. 2 is an edge elevation of this comb;

Figs. 3 and 4 are two side elevations; and

Fig. 5 is a plan of a detail.

The comb represented for treating the scalp has a back part 1 of vulcanite, synthetic plastic or the like which is fitted with teeth 2 on the side opposite the back. Provided in the back part 1 and in the teeth 2 are bores 3 which pass longitudinally through the teeth and which have a wider part 4 towards the back. The shoulders 5 between the wider parts 4 and the narrower bores 3 which open at the tips of the teeth are covered with packing rings 6, each of which is held by a sleeve 8 which is provided with a screw-threaded head 7 and which is screwed into an internal screw-thread of the wider part 4 of the bore 3. Arranged in each of these sleeves 8 is a second sleeve 9 which has, on its end that is directed towards the tip of the tooth 2, a valve cone 10 which co-operates with the packing ring 6 which serves as a valve seating and which has a conical recess for this purpose. Pressed tightly into the sleeve 9 is a pin 11 of vulcanite or the like, the front part of which passes through the narrow part of the bore 3 and projects beyond the tip of the tooth 2. A clearance of 0.1 to 0.2 mm. is left between the inside of this narrow part of the bore 3 and pin 11 this; clearance is shown enlarged in Fig. 1 for the sake of clearness. The screw-threaded

2

head 7 has a cross-bar 12 in which a guiding aperture 13 (Fig. 5) for the back part of the pin 11 is provided. Inserted into the sleeve 8 is a compression spring 14 which rests against the cross-bar 12 and presses the valve cone 10 on to the packing ring 6 which acts as a valve seating. The sleeve 9 is shorter than the sleeve 8 and, when the valve cone 10 rests on the packing ring 6, the distance of the end of the sleeve 9 from the cross-bar 12 is somewhat smaller than the length of the part of the pin 11 that is projecting beyond the tip of the tooth 2. Fitted tightly on the back part 1, which has a shoulder 15, is a flat casing 16 which is provided with a filling opening that is closable by means of a closing screw 17. This casing 16 forms the container for the substance with which the scalp is to be treated.

For treating the scalp, the comb is passed through the hair, precisely as when it is being combed, and is pressed lightly on to the head. When this is being done, the ends of the pins 11 that project from the teeth 2 are pressed back into these teeth; the result of this is that the sleeves 9, which rest firmly on the pins 11, are displaced in the sleeves 8 towards the back of the comb and the valve cones 10 are raised from the packing rings 6 that act as valve seatings. The substance which is contained in the casing 16 and with which the scalp is to be treated can now flow through the sleeves 8 and the interspaces between the pins 11 and the inside of the bores 3 in the teeth 2 directly on to the scalp and act thereon without being hindered by the hair.

Owing to the aforesaid dimensioning of the length of the sleeves 9, the pins 11 cannot be pushed back completely into the teeth 2 but only to such an extent that the sleeve 9 strikes the cross-bar 12 of the sleeve 8, so that dandruff or other foreign matter cannot enter the bores 3 and clog them.

If a liquid is employed for treating the scalp, then, on pressing the comb on to the head, the liquid flows automatically through the sleeves 8 and the bores 3 on to the scalp. If required, by pressing together the broad sides of the casing 16, which is made of sheet metal or a suitable, elastic synthetic plastic, a pumping action, which promotes the discharge of the liquid from the bores 3, can be obtained. If the scalp is to be treated with an ointment, a rubber bulb 18 or other suitable device is advantageously connected to the casing 16 for the purpose of applying pressure to the ointment in the casing 16 and forcing it out through the sleeves 8 and the bores 3.

I claim:

1. A comb for treating the scalp, comprising teeth provided with bores passing through them longitudinally, a valve in each of said teeth, spring means for keeping said valve closed, said valve having a valve cone, said valve cone having a pin for lifting said valve cone from the valve seating and thus opening said valve and said pin projecting from the tip of said tooth and passing through its bore with clearance, each said bore having a wider part towards the back part of the comb, a packing ring on the shoulder terminating said wider part, a first sleeve inserted in said wider part and holding said packing ring in position on said shoulder, a second sleeve arranged in said first sleeve and having said valve cone on its end that is directed towards the tip of the tooth, said spring means being in the form of a compression spring and arranged in said first sleeve and said pin being tightly pressed into said second sleeve, a container for the substance intended for the treatment of the scalp, said container being arranged on the back part of the comb and consisting of a casing fitted tightly on the back part of the comb and provided with a filling opening and the interior of said container and said first sleeve being

in communication, and a device connected to said filling opening for the purpose of applying pressure to the substance in said container.

2. In a comb for treating the scalp, in combination, a plurality of teeth integrally connected to each other at one end to form a plate-like attaching portion and terminating, respectively, in pointed ends, each of said teeth being formed with a central stepped bore passing longitudinally therethrough, each of said bores having at said one end of said teeth a first portion having a diameter larger than the second portion of said bore; removable bushings located in said first portions of said bores respectively and fixedly attached to the respective teeth, said bushing having exterior threads thereon and being individually screwed into said first portions of said bores respectively so that said bushings can be individually removed for cleaning; a plurality of valves respectively located in said bushings, said valve means being movable between a first position in which said valve means close said bores and a second position in which said valve means provide a passage through said bores, said valve means tending to remain in said first position; a plurality of lifting rods respectively fixedly attached to said plurality of valve means and extending respectively longitudinally and with clearance through said bores and said bushings, said lifting rods respectively having free end portions extending beyond said pointed ends of said teeth, said lifting rods moving said valve means from said first position to said second position when said free end portions of said rods are pressed against the scalp to be treated, there being very small clearance between said lifting rods and said second portions of said bores to prevent extraneous matter entering therebetween; and stop means respectively connected to said bushings and cooperating with said valve means for preventing said free end portions of said lifting rods from entering entirely into said bores when said free end portions are pressed against the scalp, said stop means comprising individual bridge portions fixedly connected across each of those ends of said bushings which are located remote from said pointed ends of said teeth, said valves being adapted to abut against said bridge portions when said free end portions are pressed against the scalp.

3. In a comb for treating the scalp, in combination, a plurality of teeth integrally connected to each other at one end to form a plate-like attaching portion and terminating, respectively, in pointed ends, each of said teeth being formed with a central stepped bore passing lon-

gitudinally therethrough, each of said bores having at said one end of said teeth a first portion having a diameter larger than the second portion of said bore; removable bushings located in said first portions of said bores respectively and fixedly attached to the respective teeth, said bushings having exterior threads thereon and being individually screwed into said first portions of said bores respectively so that said bushings can be individually removed for cleaning; a plurality of valves respectively located in said bushings; said valves being movable between a first position in which said valves close said bores and a second position in which said valves provide a passage through said bores; spring means located in said bushings and operatively connected to said valves, respectively, said spring means tending to keep said valves in said first position; a plurality of lifting rods respectively fixedly attached to said plurality of valves and extending respectively longitudinally and with clearance through said bores and said bushings, said lifting rods respectively having free end portions extending beyond said pointed ends of said teeth, said lifting rods moving said valves from said first position to said second position when said free end portions of said rods are pressed against the scalp to be treated, there being very small clearance between said lifting rods and said second portions of said bores to prevent extraneous matter entering therebetween; and stop means respectively connected to said bushings and cooperating with said valves for preventing said free end portions of said lifting rods from entering entirely into said bores when said free end portions are pressed against the scalp, said stop means comprising individual bridge portions fixedly connected across each of those ends of said bushings which are located remote from said pointed ends of said teeth, said valves being adapted to abut against said bridge portions when said free end portions are pressed against the scalp.
